METHOD OF MAKING DIES

Sven Ragnar Lange, Stockholm, Sweden, assignor
to Aktiebolaget Elektrolux, Stockholm, Sweden,
a corporation of Sweden

Application September 23, 1947, Serial No. 775,662
In Sweden October 17, 1946

18 Claims. (Cl. 76—107)

1

My invention relates to a method for making dies for machine tools.

In making dies it has usually been the practice to form an opening or aperture therein by machining, milling, grinding and filing operations, for example. Making dies in this manner having openings or apertures of precise dimension and shape is not only tedious and time-consuming, but is costly and usually requires the services of artisans who are especially skilled in die-making.

An important object of the invention is to provide an improved method of making dies of this type which overcomes the disadvantages of existing practices and is simple and inexpensive.

Another object of the invention is to provide such an improved method for making dies in which a punch or punches with which a die is ultimately used may be advantageously employed to manufacture the die.

A further object of the invention is to employ in such improved method an auxiliary die for making a final die adapted for use with the punch of a machine tool for stamping work pieces.

A still further object of the invention is to employ in such improved method an auxiliary die formed of a plurality of plates which are joined together to form a unitary body, the individual plates having openings or apertures formed therein which are substantially in alignment.

While the method of the invention can be practiced advantageously to manufacture dies having openings or apertures of any desired shape, the method lends itself to the making of dies having apertures which are of non-circular shape for stamping irregular and intricate shaped apertures or notches in work pieces. Moreover, the method of the invention can be employed for simultaneously manufacturing a number of dies with precision, whereby several dies which are exact duplicates can be made with very little deviation in dimensions from one another.

My invention will be better understood from the following description when taken into connection with the accompanying drawing, and its scope will be pointed out with particularity in the appended claims.

In the accompanying drawing Fig. 1 diagrammatically illustrates an initial step in manufacturing a die in accordance with the invention; Fig. 2 diagrammatically illustrates an intermediate step in manufacturing the die; Fig. 3 diagrammatically illustrates an advanced step in manufacturing the die; Fig. 4 is a sectional view, taken at line 4—4 of Fig. 5, of a die made in accordance with the invention; Fig. 5 is a top plan

2

view of the die shown in Fig. 4; Fig. 6 is a sectional view of an auxiliary die formed in an intermediate step of the method and with the aid of which the die shown in Figs. 4 and 5 is manufactured in an advanced step; and Fig. 7 diagrammatically illustrates a step of the invention subsequent to that shown in Fig. 3.

According to the present invention a punch of a machine tool is made in the customary manner to form an opening or notch of a definite shape in work pieces, as in a stamping press, for example. In Fig. 1 are illustrated a number of punches 10 formed to stamp openings in work pieces which are of the shape shown in Fig. 5. The punches 10 are mounted in a punch holder 11 arranged in any suitable manner in a chuck 12 adapted to be installed for vertical reciprocatory movement in a stamping press.

In making a die in accord with the invention the punches 10 are employed to stamp a pad 13 to form what may be referred to as a first auxiliary die. The pad 13 is preferably formed of material which is hard and relatively tough and in which sharply defined impressions can be stamped by the punches 10. By way of example, I have found a pad 13 formed of a resinous phenolic condensation product, such as that commercially known as "Bakelite," very satisfactory. The pad 13 may consist of suitable fabric impregnated with such a resinous product. It is to be understood that other materials possessing physical properties generally similar to "Bakelite," as regards toughness and durability, may be used. In stamping the pad 13 the latter is placed in a chuck of the stamping press and the punches 10 are forced downwardly into the pad to form recesses 14, as shown in Fig. 1. The recesses 14 are well defined and have sharp edges and conform to the cross-sectional shapes of the punches 10.

The punches are moved upwardly and a metallic plate 15 is then placed over the stamp pad 13, as shown in Fig. 2. The punches 10 are then forced downwardly again to stamp openings in the plate 15 with the stamped pad 13 serving as a first auxiliary die. The plate 15 is preferably formed of relatively hard metal sheeting, such as hardened strip steel or like material, for example; and such plate, together with a number of similarly stamped plates, are bundled into a package to form a second auxiliary die in accord with the invention.

In order to facilitate the making of the second auxiliary die according to one embodiment of the invention, the pad 13 is removed from the stamping press and replaced by a hardened steel back-

ing plate which has been plane ground. The stamped plate 15 is placed on the backing plate on top of which in turn is positioned a plate formed of relatively soft material, such as brass or aluminum, for example. The punches 10 are then forced downwardly to stamp the plate of soft material while the stamped plate 15 serves as an auxiliary die. The plate of soft material is then removed while the material stamped therefrom and forced into the bottom parts of the openings in the stamped plate 15 is allowed to remain therein.

A second plate 15 like the first stamped plate 15 is then placed over the latter, and the punches 10 forced downwardly to stamp such second plate while the first stamped plate 15 serves as an auxiliary die. The material stamped from the second plate 15 by the punches 10 is pushed downwardly such a distance that the lower parts thereof are disposed within the openings in the first stamped plate 15 and the upper parts thereof are disposed within the stamped-out portions of the second plate 15. In this way the stamped-out material, which may be referred to as cuttings or leavings, are effectively used as a joint and guide between the first and second stamped plates 15.

A third plate 15 is placed over the second plate 15 and stamped by the punches 10, the material stamped from such third plate being forced downwardly such a distance into the stamped-out portions of the second plate that it effectively joins and holds together the second and third plates. Additional plates 15 are successively placed on the package of plates being built up and stamped in the manner just described until a bundle of desired thickness is obtained. In this way the material punched out of each plate 15 is partially moved into the opening of the next lower plate. While building up the bundle of plates 15 the stamped material is allowed to remain in the cut-out portions to hold the plates together. Before the cuttings or leavings are removed, the plates 15 are joined together in any suitable manner, as by welding or riveting, for example, to form a unitary body 17 which may be referred to as the second auxiliary die. As shown in Fig. 6, the plates 15 are securely fastened together by countersunk rivets 16, and the leavings or cuttings then removed from the stamped-out portions of the plates.

The final die is formed from a block or plate 18 of ferrous metal which is relatively soft and capable of being hardened. In making the die from the plate 18, the latter is placed on the second auxiliary die 17, which, in turn, is fixed to and rests on a surface ground hardened base member 19. After the plate 18 and second auxiliary die 17 are oriented and secured in position, the punches 10 are forced downwardly to stamp the openings in the plate 18, as shown in Fig. 3.

The plate 18 is surface ground and the openings formed therein are cleaned, that is, reamed or drifted, so as to provide suitable clearance or play between the punches and the openings in the die 18. I accomplish this by upsetting the ends of each punch 10 to form a flange which serves as a trimming edge or drift ledge, as indicated at 20 in Fig. 7. The punches 10 are then mounted in the stamping press and forced downwardly through the openings in the die 18, whereby the die openings are effectively cleaned to provide the desired clearance between each punch and the die opening through which it passes.

In order to make the punches 10 and die 18 ready for use to operate on work pieces, the up-

set ends or flanges 20 of the punches are removed in any suitable manner, as by grinding, for example. The final die or pad 18 is carbonized or charged with carbon and hardened in any well known manner. After being hardened, the die 18 is desirably tempered and then ground smooth.

In order to illustrate better the method of making dies in accordance with the invention, the following example of one application of the method is given for the purpose of illustration only. A pad 13 was employed formed of fabric impregnated with "Bakelite," and the punches 10 forced downwardly therein for a distance of about 1 mm. to form the recesses 14. A plate 15 formed of hardened strip steel, having a thickness of about 1.1 mm., was then positioned over the pad 13 and stamped by the punches to form openings therein. The pad 13 was then replaced by a surface ground hardened steel plate over which the stamped plate 15 was positioned. A brass plate having a thickness of about 0.5 mm. was placed over the stamped plate 15, and the punches 10 moved downwardly to force the stamped brass material into the lower part of the openings in the plate 15.

A bundle of hardened steel plates 15, each having a thickness of about 1.1 mm., was then built up in the manner described above until a package of six plates was produced. As each added plate was stamped, about one-half of the thickness of the leavings or cuttings occupied the space in one plate and the other half thereof occupied the space in the next higher plate in the plate bundle. Before removing the leavings or cuttings, the plates were joined together by countersunk rivets 16.

The second auxiliary die formed by the bundle of plates 15 was positioned over and fixed to the ground surface of a hardened steel plate, and a plate 18 of soft iron positioned over the plate bundle 17, such plate 18 having a thickness of about 5.5 mm. The plate 18 was stamped in the manner previously described after which the openings formed therein were cleaned out by upsetting the ends of the punches 10. Thereafter, the upset ends of the punches were ground smooth and the plate 18 case-hardened, tempered and ground smooth to make it ready for operating on work pieces.

It will now be seen that I have provided an improved method of making dies in which the punch or punches with which the die is intended to be used are advantageously employed to manufacture the die. The method of the invention lends itself to making several dies at the same time from a single block or plate which can thereafter be subdivided to provide the individual dies. When several punches are employed, as in the embodiment described, it may sometimes be desirable initially to operate only a few punches in the different stamping operations, and progressively increase the number of punches used so as to reduce the pressure required of the machine tool in the stamping operations.

The plate bundle or second auxiliary die 17 desirably is formed of plates each having a thickness which is less than that of the plate from which the final die is produced. The overall thickness of the plate bundle 17 preferably is approximately equal to or possibly greater than the plate or block 18. By forming the plate bundle of sheets of hard strip steel or like material, a second auxiliary die is provided which is extremely effective for producing the final die.

In order to facilitate making the pad 13, the punches 10 may be initially brought against the pad so as to mark an outline thereon of the stamping which is ultimately made by each punch. A region of the pad 13 within each marked outline produced may be drilled to a depth of about 3 mm. by a drill or milling tool of such size that the drilled opening is well within the outline marked by each punch. When each punch is subsequently actuated to form a recess 14 in the drilled pad, less pressure is required in the stamping operation, and the tendency for the material to creep is substantially reduced so that recesses having extremely sharp edges will be produced.

It is to be understood that the method described herein is susceptible of modifications and changes without departing from the spirit and scope of the invention. Thus, in certain instances it may be preferable to use the pad 13 as an auxiliary die for stamping all of the plates 15 which are to be joined together to form the plate bundle or second auxiliary die 17. It is also possible to make the punch or punches from a finished or completed die. Therefore, I do not wish to be limited to the particular embodiment described, and I intend in the following claims to cover all modifications which do not depart from the spirit and scope of my invention.

What is claimed is:

1. A method of making a final die for use with a punch of a machine tool, which includes forming a first auxiliary die by stamping with the punch a pad comprising a phenolic condensation product or like material possessing generally similar physical properties as regards toughness and workability, forming a second auxiliary die by a process which includes the step of stamping an element with the punch while such element is backed up by the first auxiliary die, and stamping a part with the punch while such part is backed up by the second auxiliary die to form the final die adapted for use with the punch for operating on work pieces.

2. The method set forth in claim 1 in which said pad comprises fabric impregnated with said phenolic condensation product or like material possessing generally similar physical properties as regards toughness and workability.

3. The method set forth in claim 1 in which the second auxiliary die comprises a number of relatively hard metallic plates of which said element constitutes one such plate, each plate having a thickness less than that of said part, the second auxiliary die being formed by a process which further includes the steps of stamping openings in the plates with the punch, and uniting the plates to form a unitary body constituting the second auxiliary die in which the openings formed by the punch are substantially in alignment.

4. The method set forth in claim 3 in which the final die comprises a metallic body, the plates when united forming said unitary body having an overall thickness which is substantially at least as great as the thickness of said metallic body.

5. In the method set forth in claim 1 in which the second auxiliary die comprises a number of relatively hard metallic plates of which said element constitutes one such plate, each plate having a thickness less than that of said part, the second auxiliary die being formed by a process which further includes the steps of stamping openings in all of said plates with the punch, and uniting the plates to form a unitary body constituting the second auxiliary die in which the

openings formed by the punch are substantially in alignment.

6. In the method set forth in claim 1 in which the second auxiliary die comprises a number of relatively hard metallic plates of which said element constitutes one such plate, each plate having a thickness less than that of said part, the second auxiliary die being formed by a process which further includes the steps of stamping an opening in said plates while successively employing as an auxiliary die member the plate previously having an opening stamped therein, and uniting the plates to form a unitary body constituting the second auxiliary die in which the openings formed by the punch are substantially in alignment.

7. In the method set forth in claim 6 which includes the step of placing said one stamped plate on a hard base member while serving as an auxiliary die for stamping an opening in another or second plate with the punch.

8. In the method set forth in claim 7 which includes the steps of stamping the opening in the second plate so that the material punched therefrom partially moves into the opening in said one plate to hold the first and second plates together as an auxiliary die member while stamping a third plate, and stamping the opening in the third plate so that the material punched therefrom partially moves into the opening in the second plate to hold the second and third plates together.

9. In the method set forth in claim 8 which includes the steps of stamping an opening with the punch in a relatively soft metallic sheet formed of brass or aluminum or like material, for example, while employing said one or first stamped plate as an auxiliary die member so that the material punched therefrom moves into the opening in said one plate, said metallic sheet being of less thickness than the first stamped plate, removing said sheet while leaving the punched material therefrom in the opening in said first plate, and then utilizing said first plate as an auxiliary die member for stamping an opening in the second plate with the punch.

10. In the method set forth in claim 1 in which the second auxiliary die comprises a number of relatively hard metallic plates of which said element constitutes one such plate, each plate having a thickness less than that of said part, the second auxiliary die being formed by a process which further includes the steps of stamping an opening in said plates while successively employing as an auxiliary die member the plate previously having an opening stamped therein, keeping each plate on top of the previously stamped plate so that the material punched therefrom partially moves into the opening in the next lower plate to hold the plates together by the material punched out of the openings formed in the plates, uniting the plates to form a unitary body constituting the second auxiliary die in which the openings formed by the punch are substantially in alignment, and then removing the punched material from the openings before utilizing the second auxiliary die to form the final die.

11. In the method set forth in claim 1 in which said part comprises a body of ferrous metal which is relatively soft, the further step of hardening said body after being stamped with the punch.

12. In the method set forth in claim 11 which includes the step of reaming or drifting the opening in said part before the latter is hardened with the aid of a punch which is flanged to provide a reaming or drift ledge.

13. In the method set forth in claim 12 which includes the step of grinding the punch to remove the drift ledge when reaming or drifting is completed.

14. In the method set forth in claim 1 in which said part comprises a body of relatively soft ferrous metal, the steps which include upsetting the punch to form a drift ledge, reaming or drifting the opening in said part to clean out the latter, grinding the upset punch to remove the drift ledge, and hardening said part when the opening therein is cleaned.

15. In the method set forth in claim 1 which includes the steps of initially bringing the punch against said pad so as to mark an outline thereon of the stamping to be effected by the punch, and drilling said pad within the marked outline to facilitate the stamping of said pad.

16. A method of making a final die for use with a plurality of punches associated with a machine tool, which includes forming a first auxiliary die by stamping with the punches a pad comprising a phenolic condensation product or like material possessing generally similar physical properties as regards toughness and workability, forming a 25 second auxiliary die by a process which includes the step of stamping an element with the punches while such element is backed up by the first auxiliary die, and stamping a part with the punches while such part is backed up by the second auxiliary die to form the final die adapted for use with the punches for operating on work pieces.

17. In the method set forth in claim 16 which includes the steps of successively increasing the number of punches employed on the machine tool 35 when stamping said pad so as to reduce the pressure required of the machine tool to effect said stamping and also counteract creeping of the material.

18. In the method set forth in claim 16 in which the second auxiliary die comprises a number of plates formed of steel or like material of which said element constitutes one such plate, each plate having a thickness less than that of said part, the second auxiliary die being formed by a process which further includes the steps of stamping openings in the plates with the punches, and uniting the plates to form a unitary body constituting the second auxiliary die in which the openings formed by the punches are substantially in alignment.
